INFANT'S GARMENT

Nina C. Oswald, New York, N. Y.

Application September 5, 1945, Serial No. 614,489

4 Claims. (Cl. 2—69.5)

1

This invention relates to children's garments and particularly to outer garments for covering babies and young children when in bed, in baby carriages, in automobiles, and the like. In general, it is an object of the invention to provide an improved garment which may be safely and effectively used in place of a blanket to cover a small child, but which will be impossible for him to throw off. A more specific object is the provision of a sleeping garment which provides within it a wide latitude for leg and body movement but which at the same time fully protects the arms while leaving the hands free from the entangling folds of the blanket.

Everyone who has cared for babies knows the difficulties involved in preventing them from throwing off their blankets, and can hardly have helped noticing the frustration of the children in trying to turn or otherwise move when their covers are pinned down. Also apparent is the difficulty in the use of a child's hands unless the whole arm is exposed. Ordinary covers are, moreover, always a source of danger of smothering, due to tendencies of babies to crawl under them.

Innumerable efforts have been made in the past to solve these problems but they have all fallen short of attainment of a solution. For the most part, if proper covering was effected movement has been too restricted in one or more respects; or if movement was permitted, covering was ineffective. If both factors were taken into consideration, the arms or hands of the wearer were insufficiently protected or unduly restricted.

With the foregoing and other considerations in view, there is provided in accordance with the present invention a garment which allows the wearer freedom for practically all types of twisting, stretching, rolling, reaching, grasping and kicking movements, while fully protecting his body, arms, and legs at all times. Preferably in many instances the garment is so formed as to leave the hands of the wearer free, permitting him to readily feed or entertain himself; and garments embodying the invention in its more specific aspects are provided with an openable closure at their lower ends, permitting ready access to the interior of the garment by those taking care of the child.

The invention accordingly comprises an article of manufacture possessing the features, properties, and the relation of elements which will be exemplified in the article hereinafter described and the scope of the application of which will be indicated in the claims.

For a fuller understanding of the nature and

2

objects of the invention, reference should be had to the following detailed description taken in connection with the accompanying drawing, in which:

5 Figure 1 is a front view of a garment embodying the invention;

Fig. 2 is a fragmentary view corresponding to the lower left-hand portion thereof and illustrating a modification; and

10 Figs. 3 and 4 are similar views corresponding with the upper left-hand portion of Fig. 1 and illustrating other modifications.

An important feature of the invention is the provision of a body portion which is wider than the distance between the out-stretched elbows of a wearer whose wrists are encircled by sleeve portions extending laterally from the body portion. In the garment exemplified in Fig. 1, the body portion 5 is of such width throughout its length as to extend outwardly a greater distance than the elbows 6 of a child of the size indicated in the dotted lines whose wrists 7 are encircled by sleeve portions 8. In the present instance, the garment is formed of two superposed substantially rectangular pieces 9 and 10 of material, for instance flannel, having a width slightly greater than the distance from wrist to wrist of the outstretched arms of a child for whom it is intended. Desirably, the two pieces may be a single unit folded over at the top at 11. Stitching 12 joins the pieces at their side edges except at the upper portion where wrist openings 13 are provided. Stitching 14 extends inwardly from these openings to provide the sleeves 8. A neck opening is

35 provided at 15, and, in accordance with the invention in its more specific aspects, there is provided in the upper or forward piece a central slit 16 which may be opened to remove the child or to adjust his nighty. This slit may be closed by any

40 suitable means such, for instance, as the zipper 17 exemplified. As above indicated, the distance between the ends of the sleeves is in the present instance somewhat greater than the distance between the outstretched arms of a child of the size indicated in dotted lines giving rise to folds or wrinkles 18. This is a desirable normal condition as it gives greater freedom of movement and also allows for growth of the child. Similarly, the length of the garment is, as shown, somewhat greater than the distance from the neck to the feet of a child for whom the garment is intended.

45 While, pursuant to the invention in certain of its broader aspects, the bottom of the garment may be left open, it is ordinarily closed to pre-

vent the garment from riding up on the wearer with consequent exposure of his feet or legs. Accordingly, there are provided buttons 19 or other suitable fastening means such for example as the zipper 20 indicated in Fig. 2.

Desirably a wide binding of soft material, as for example rayon, is provided at the free edges of the openings of the garment as at 21, 22 and 23.

While it is usually advantageous to let the hands of the child protrude from the wrist openings, the garment may be continued outwardly to provide bagged ends or mittens as indicated at 24 in Fig. 3. Even in this case the child has considerable use of his hands.

As will be apparent various modifications may be made without departing from the invention in its broader aspects. For example, the material of which the garment is formed may be cut to provide a somewhat narrower body portion with protruding sleeves, the body portion being nevertheless sufficiently wide to extend beyond the elbows of the outstretched arms of a child whose wrists are encircled by the sleeves 25, as shown in Fig. 4.

The form exemplified in Fig. 1, however, not only has the advantage of permitting the child to have his hands entirely free so that he may readily hold his bottle or entertain himself as with a rattle but the provision of the sleeves 8 prevents the child from easily pulling his hand into the interior of the garment where it will be imprisoned.

Garments formed in accordance with the invention will fit equally well over nightgowns or pajamas. The child can sleep in any position, on his stomach, side or back; and can change his position at will. Moreover, with the bottom of the garment open, the child can stand or walk about in his crib and still be completely covered.

The garment accordingly provides a highly satisfactory solution to the problem of providing an effective and convenient outer covering for a child who is being taken for an airing or who is quietly playing, as well as for a sleeping child.

What I claim is:

1. A child's garment having short sleeve-like portions and a roomy body portion extending laterally to points substantially in line with the ends with said sleeve-like portions and outwardly of the elbows of a wearer whose wrists are

encircled by said sleeves when his arms are outstretched sideways, the sleeves being formed by stitching separating them from the body portion which is contiguous to said sleeve-like portions.

- 5 2. A garment formed of two superposed pieces of substantially rectangular material, united at their upper ends except for a neck opening and at their sides except for wrist openings and stitched inwardly a short distance from the lower 10 end of each of the wrist openings to provide hand-receiving tunnels extending a substantial distance from the side margins of the garment to encircle a wearer's hands when withdrawn thru said openings.
- 15 3. A child's garment comprising two superposed portions of material so joined at the top as to provide a neck opening and at their sides as to provide hand openings, and joined for a distance inwardly of the lower end of each hand 20 opening to provide short sleeve portions above the line of jointure so that the sleeve portions thus provided will still encircle the child's hands when withdrawn thru said openings, and a roomy body portion extending in a downward direction 25 from the outstretched lines of jointure and the space intermediate the same, said portions of material extending continuously across said lines of jointure.
4. A child's garment as set forth in claim 3 30 wherein there is provided an openable closure at the lower end of the body portion.
